DRAWING DIE

Adrian P. Roux, Oriskany, N. Y., assignor to
 General Cable Corporation, New York, N. Y., a
 corporation of New Jersey

Original application September 12, 1929, Serial
 No. 391,994. Divided and this application July
 8, 1930. Serial No. 466,442

8 Claims. (Cl. 205—29)

This invention relates to drawing dies and has
 for an object the provision of an improved die.
 This application is a division of my application,
 Serial Number 391,994, filed September 12th,
 5 1929.

Although there is a constant search for sub-
 stitutes for diamond dies, up to the present time
 none has been found which possesses all the de-
 sirable qualities of diamond. But diamonds are
 10 very expensive especially in larger sizes and are
 difficult to mount satisfactorily. They are also
 brittle and have other undesired characteristics.
 As will be disclosed hereinbelow I have provided
 a mounting for diamonds or other hard die cores
 15 which permits the use of very small sizes, and
 which furnishes so substantial a backing or ma-
 trix for them that their tendency to split is
 greatly reduced and they can be used until only
 a thin shell or ring remains.

20 It has been the practice to some extent to
 cast a body or matrix of iron, steel, bronze or
 other metal upon the diamond or other hard ob-
 ject as a core and then to pierce the blank thus
 formed through the hard core to form the die.

25 But the matrix materials heretofore used or pro-
 posed have not proven satisfactory. They are
 not sufficiently hard or are too ductile or too elas-
 tic to properly take the strains transmitted
 30 through the core; or they do not closely overlie
 and conform to the core due to improper shrink-
 age or non-affinity for the core-piece. According-
 ing to the present invention a suitable matrix
 material and a proper process of surrounding
 35 the core piece therewith have been discovered

so that the resultant die is adequately backed,
 the matrix material being sufficiently hard, in-
 elastic, non-ductile and non-brittle so that it will
 not readily split or permit the core piece to split
 40 and so closely and evenly overlying the core
 piece that no inequality of strain is permitted.
 Indeed, in the case where a diamond core is used
 the matrix material is found to be so closely
 adherent to the core as apparently to form a
 45 union therewith.

50 The nature and objects of the invention will
 be better understood from an exposition of an
 exemplary and illustrative embodiment thereof
 when considered in connection with the accom-
 panying drawing, wherein:

Fig. 1 is a cross-section of a die and holder,
 the view being taken on the line 1—1 of Fig. 2;

Fig. 2 is a plan view thereof; and

Fig. 3 is a section through a mold assembly
 with the die in process of formation therein.

55 As shown in the drawing a hard core 10, for

example, a diamond, is encased in a matrix 11
 of the desired material. These elements form-
 ing the die proper are closely fitted into a hold-
 er 12 and if desired may be driven or welded
 therein. The assembly thus formed is in con-
 dition for mounting in a drawing machine so
 as to have wire or the like drawn therethrough
 in the direction of the arrow A in Fig. 1.

The matrix material at present preferred may
 have the following composition:

	Per cent
Iron	10
Nickel	15
Tungsten	30
Tungsten carbide	45
	70

But either iron or nickel may be used alone with
 the tungsten carbide, or the tungsten may be
 omitted, or the ratios of the various constituents
 may be varied. In some cases cobalt may be
 75 substituted for the iron or nickel or tungsten or
 all of them. In any case the composition formed
 will be extremely hard and tough and will have
 good die-forming qualities of itself.

The die may be formed in a welding-carbon
 mold 15 disposed between water-cooled electrodes
 E1 and E2. The matrix material is preferably
 finely divided (say 300 mesh) tungsten carbide
 and metal which have been thoroughly mixed.
 The diamond or other core piece is held centered
 80 by projections 16 formed on the ends of carbon
 plugs 17 which also confine the matrix material
 about the core piece.

When thus assembled a considerable resilient
 pressure (say 1100 pounds per square inch) is
 imposed upon the carbon plugs 17 and electric
 current is turned on the electrodes. This sinters
 85 the matrix material and causes it to shrink in
 volume, the projections 16 of the carbon plugs
 17 burning away or breaking down sufficiently
 to allow the plugs to follow up and maintain
 pressure upon the matrix material.

After sintering the pressure is left on the plugs
 while the die blank is allowed to cool between
 the water-cooled electrodes. It is an inherent
 fact that the matrix composed of these constitu-
 ents and formed in this manner will be substan-
 tially free from voids, which is to say, that the
 voids, which are incident to sintering without
 pressure are so markedly reduced as to make
 it proper to say that the material is substantially
 90 free from voids.

Upon cooling, the die blank thus produced
 is pierced through the core piece with the re-
 stricted portion of the pierced bore where the

110

greatest drawing strains will be imposed located in the hard core piece. Normally the indentations in the blank left by the plug projections 16 serve to locate the line of piercing. The blank 5 is then mounted in the holder 12 ready to be placed on a machine.

After the bore has become worn by use it may be re-bored for larger sizes and this may be repeated until the core is practically all used up 10 to a thin outer shell. This benefit is attained in part because of the superior matrix material provided which is so hard and otherwise suitable that it may itself well serve for the flaring portions of the drawing bore.

15 Furthermore, with such a matrix, much smaller diamonds or other hard cores may be successfully used initially than with any known settings. For example, where $\frac{1}{4}$ carat diamonds were formerly used for steel settings, and 1 carat diamonds for bronze settings, $\frac{1}{8}$ carat diamonds can by the present invention be used with equally good results; and likewise where $1\frac{1}{2}$ carat diamonds were required for steel settings and 4 carat diamonds for bronze settings, $\frac{3}{4}$ carat 20 diamonds can now be used. The saving, it will be realized, will be much greater than is represented by the proportions in size because of the fact that diamonds and other gems are disproportionately cheaper in the smaller sizes.

25 30 Also the cost of manufacture is greatly reduced by the present process. By comparison, in a large shop it has been found that sixty (60) of the new die settings can be made in the time that was formerly required to make ten (10) by 35 the old processes and materials. But above this is the fact that the dies made according to the present invention are practically all found by test to be free of faults while cast-metal set dies previously made were subject to many flaws and 40 faults, most of which could not be readily detected. So that, not only the settings, but the much more valuable cores were frequently broken before they had given much service in the expected way.

45 In service the setting material is unaffected by high temperatures which formerly rendered

useless dies having settings of other materials such as steel, bronze, etc.

The above description of the particular embodiment of the invention is illustrative merely and is not intended as defining the limits of the 80 invention.

What I claim is:

1. A drawing die comprising a diamond core embedded in a matrix formed of a tungsten carbide composition which is substantially free from voids, the die being pierced through the core to form the drawing bore and the restricted portion of the bore being located in the core. 85

2. A drawing die comprising a hard natural gem core embedded in a matrix formed of a tungsten carbide composition which is substantially free from voids, the die being pierced through the core to form the drawing bore and the restricted portion of the bore being located in the core. 90

3. A drawing die comprising a hard natural gem core embedded in a matrix formed of a composition including tungsten carbide and a metal of the iron group. 95

4. A drawing die comprising a hard natural gem core embedded in a matrix formed of a composition including tungsten carbide and a metal. 100

5. A drawing die comprising a hard natural gem core embedded in a matrix formed of a composition having approximately the composition, 105 iron 10%, nickel 15%, tungsten 30%, and tungsten carbide 45%.

6. A drawing die comprising a hard natural gem core embedded in a matrix formed of material including tungsten carbide. 110

7. A drawing die comprising a diamond core embedded in a matrix including a hard metal carbide which closely conforms to all contours of the core and intimately contacts with the same. 115

8. A drawing die comprising a diamond core 115 and an enveloping matrix of a composition which includes tungsten carbide, the matrix closely conforming to all contours of the core and intimately contacting the same.
